UNITED STATES PATENT OFFICE.

COLIN DOUGLAS BARRETT, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR AN ARTICLE OF MANUFACTURE.

53,061.

Specification for Design.

Patented Mar. 11, 1919.

Application filed December 6, 1918. Serial No. 265,649. Term of patent 14 years.

To all whom it may concern:

Be it known that I, COLIN DOUGLAS BARRETT, a citizen of the United States, and a resident of Providence, in the county of Providence and State of Rhode Island, have invented a new, original, and ornamental Design for Articles of Manufacture, of which the following is a specification, reference being had to the accompanying drawing, forming part thereof.

The figure in the drawing is a view of the obverse side of the article of manufacture, showing my design, the same comprising an embellished article of manufacture and as shown is embodied in a roll of honor frame, although the same may also be embodied in a memorial tablet or various other similar articles.

I claim—

The ornamental design for an article of manufacture, as shown.

COLIN DOUGLAS BARRETT.
